UNITED STATES PATENT OFFICE

JOSEPH R. MAHAN, OF TOLEDO, OHIO, ASSIGNOR TO THE NATIONAL SUPPLY COMPANY,
OF TOLEDO, OHIO, A CORPORATION OF OHIO

HINGED PACKING UNIT

Application filed July 2, 1931. Serial No. 548,343.

My invention relates to packing units designed particularly for packing annular spaces between casing heads and drill pipes suspended therein, but it is capable of use in 5 other devices.

It is the principal object of this invention to provide a hinged packing unit which may be opened on one side so as to be quickly applied around a drill pipe of the like, and lowered into position in the casing head in cases of emergency. Another object is to provide means for locking the hinged portions of the packing unit in their closed positions.

Referring to the accompanying drawing, 15 Fig. 1 is a vertical section on the line 1—1 on Fig. 2, showing a packing unit constructed in accordance with this invention; Fig. 2, a top plan view of the packing unit with the hinged members closed; Fig. 3, a top plan view of the 20 packing unit with the hinged members partially open; Fig. 4, a bottom plan view of the packing unit; and Fig. 5, a transverse section of the left hand portion of Fig. 2.

On the drawing, 1 designates a hollow cylindrical packing ring composed of asbestos, rubber or other suitable compressible packing material. The ring is divided longitudinally into two lateral members 2 and 3 along the planes indicated by the lines 4 and 5. The 25 line 4 is radial and the line 5 is diagonal cutting an imaginary radius preferably at about an angle of thirty degrees (30°) thereof, but it may be greater.

The upper ends of the members 2 and 3 30 have thereon the respective arcuate metal followers 6 and 7, conforming to the arcuate upper ends of the members 2 and 3, but they are spaced slightly from their arcuate outer and inner surfaces. The opposing ends of the followers 6 and 7 are spaced slightly apart so 35 that they will not mutually engage when the ring 1 is compressed and the material thereof creeps.

The lower ends of the members 2 and 3 have 40 thereon the respective arcuate metal followers 8 and 9 shaped and arranged on the lower ends of the ring 1, the same as the followers 6 and 7 are on the upper ends thereof.

The members 2 and 3 are secured to their 45 respective followers by the rivets 10 having

their heads in counterbores 11 in the followers. The ends of the ring 1 have ribs 12 and 13 seated in the grooves 14 and 15 respectively in the followers.

The opposing ends of the followers 6 and 7 55 are connected together across the line or plane 5 by the link or hinge 16 lying in recesses 17 and 18 in the edges of the followers. The ends of the link are pivotally connected to the followers by the pivot pins 19 and 20.

The end of the follower 7 adjacent to the line 4 has a recess 21 containing one end of the latch 22 pivoted on the cross pin 23 standing across the recess 21. The latch is constructed with the hook 24 which is adapted to 60 enter the recess 25 in the adjacent end of the follower 6. The hook catches over the cross pin 26 standing across the recess 25 when the members of the ring are closed as shown in Figs. 2 and 5. The hook is urged to snap into 65 locking engagement with the cross pin 26 by the spring 27 seated in the recess 21 and bearing against the tail 28 of the latch. The latch may be freed from the cross pin 26 by 70 exerting inward pressure on the tail of the latch.

Upon opening the packing unit the members 2 and 3 swing out on the link 16, the angle of the line 5 being such that the opposing or abutting ends of the members 2 and 3 75 pass each other with little or no mutual engagement. The link permits the free opening movements of the members 2 and 3, which would be impossible if only a single hinged pin were used passing through overlapping 80 ends of the followers 6 and 7. When the ring 1 is closed the ends of the members 2 and 3 are in abutting engagement along the entire planes indicated by the lines 4 and 5, but when the members commence swinging 85 open, the abutting ends of the members 2 and 3 commence to separate and move laterally 90 with respect to each other without mutual interference.

I claim:—

1. An annular ring of packing material divided longitudinally along two planes into lateral elements, one plane including the longitudinal axis of the ring and the other plane being at a substantial angle with the first 100

plane, hinged follower rings carried by the ring of packing material and a link spanning the said plane which is at a substantial angle with the first plane and pivotally connecting the two lateral elements together.

- 5 2. An annular ring of packing material divided longitudinally along two planes into lateral elements, one plane cutting the ring of packing material at an angle of 30° or more
10 with the radius of the ring intersecting the said one plane where the latter cuts the ring, a follower carried by each element, and a link spanning the plane making the said angle with the radius of the ring and pivotally
15 connecting together the adjacent ends of the followers.

3. An annular ring of packing material divided longitudinally along two planes into lateral elements, one plane cutting the ring of packing material at a substantial angle with the radius of the ring intersecting the said one plane where the latter cuts the ring, a follower carried by each element, and a link spanning the plane making the said angle with the radius of the ring and pivotally
20 connecting together the adjacent ends of the followers, the pivotal connections of the link with the said elements having constant
25 relative positions.

- 30 In testimony whereof, I hereunto affix my signature.

JOSEPH R. MAHAN.
